UNITED STATES PATENT OFFICE.

LORENZO S. GRAVES, OF ROCHESTER, NEW YORK, ASSIGNOR TO LORENZO S. GRAVES & SON, OF SAME PLACE.

ELEVATOR SAFETY DEVICE.

SPECIFICATION forming part of Letters Patent No. 319,480, dated June 9, 1885.

Application filed January 30, 1885. (No model.)

To all whom it may concern:

Be it known that I, LORENZO S. GRAVES, of Rochester, New York, have invented an Improved Elevator Safety Device, of which the following is a specification, reference being had to the accompanying drawings.

My invention relates to an improved elevator safety device, which is fully described in the following specification, and the novel features thereof specified in the annexed claims.

My improved elevator safety device is represented in the accompanying drawings, in which Figure 1 is a side elevation of the upper portion of an elevator-car embodying my improvement. Fig. 2 is a plan view of the same. Fig. 3 represents the sheave-pulley and clamping device. Fig. 4 is a section through the sheave-pulley and clamps on the line *xx*, Fig. 2. Fig. 5 is a section through the sheave-pulley on the line *yy*, Fig. 4, showing the manner of attaching the ropes thereto.

In the accompanying drawings, representing my present invention, A is the elevator-car; B B', the guideways; C C', the cross-beams, to which the car is attached; D D', the main lifting-cables; E E', the cables connected with the counterbalance-weight; F F', the sheave-pulleys, and G G' the clamping-screws. The elevator-car may be of any ordinary or preferred construction, and ornamented, if designed for use in the conveyance of passengers. The main lifting-cables D D' are connected with any suitable mechanism for raising and lowering the car, constructed and arranged in any ordinary or preferred manner for this purpose. The counterbalance-cables E E' extend upward from the car and pass over suitable pulleys, and thence downward to a counterbalancing weight, H, arranged to travel up and down in a suitable well alongside of the elevator, or in any other suitable relation therewith. Both the main lifting-cables D D' and the cables E E' connected with the counterbalance pass around the pulleys *o o' o'' o'''*, and extend laterally to the sheave-pulleys F F', which are fastened to the screws G G', the arrangement being such that in case the main lifting-cables break or become slack from any cause the counterbalance-weight, acting through the cables E E', will cause the sheaves

F F' and the screws G G' to revolve, thereby drawing the ends *v v* of the cross-beams C C' together, as indicated by the dotted lines in Fig. 3, and clamping them firmly against the opposite sides of the guideways B B', arresting the descent of the car without jar or jerk, and preventing accidents from the breaking or slackening of the main lifting-cables. The ends of the counterbalance-cables are wound one or more times about the sheaves F F', and the two sets of cables are attached to opposite sides of the sheaves, so that the strain or pull of one set of cables tends to cause the sheaves to revolve in one direction, while the strain of the other set tends to turn the sheaves in the opposite direction. The screws G G', the opposite ends of which are preferably provided with threads cut in opposite directions, as indicated in Fig. 3, may be threaded directly into the cross-beams, or they may be inserted into the nuts *r r'*, fastened to the cross-beams, the latter arrangement facilitating the setting up of the apparatus. It is obvious, however, that one end only of the screws need be threaded, the other end being provided with a collar outside of one of the cross-beams, to resist the strain caused by clamping the ends of these cross-beams against the guideways. In either case the lead of the screw should be in such a direction that the turning of the sheaves by the strain of the counterbalance-cables attached thereto will draw the ends of the cross-beams together, or move one end of one of the cross-beams toward the corresponding end of the other. The pulleys *o o' o'' o'''* are mounted so as to revolve independently of each other on suitable bolts or studs inserted in the cross-beams.

As indicated in the drawings, the main lifting cables D D' pass from the corner pulleys to the lower sides of the sheaves F F', while the counterbalance-cables pass to the upper sides of the sheaves, in order that the strain or pull of the two sets of cables may give the sheaves a tendency to revolve in opposite directions, and so that in case the strain of the lifting-cables is released or slackened the counterbalance-cables may turn the sheaves and screws, thereby clamping the ends of the cross-beams against the guideways. The ends of the cables are fastened to the sheaves, as represented in

Fig. 5, by being passed through a hole cored through the sheave and fastened therein by pouring in melted lead or Babbitt metal. They may, however, be attached to the 5 sheaves in any other preferred manner. The cross-beams are secured together by suitable bolts or struts, *s s*, and the car is supported from the cross-beams by the rods *I I*, or in any other preferred manner. The clamping- 10 beams may, if desired, be placed below the car, the cables being led around suitable pulleys, so as to leave the interior of the car unobstructed.

In the drawings I have represented the 15 clamps *v v* as formed by the ends of the cross-beams *C C'*; but it is obvious that the clamps may be independent of the cross beam or beams, if preferred, being hinged or otherwise secured thereto so that their outer ends are capable of being moved to and from the guideways. The car may be guided by the cross-beams alone, the clamp *v v* being so constructed as to bear against the inner faces of the guideways; but I prefer to apply to the car 20 the additional guides, (represented as *J J*, Fig. 1,) which may be made adjustable either in whole or in part to and from the guideways. The lower part of the car is provided with guides arranged in any ordinary or preferred 25 manner.

In order to secure equality of strain on the counterbalance-cables, they may be caused to pass around a pulley attached to the counterbalance; or they may be fastened to the ends 30 of a compensating-lever pivoted at its middle to the weight.

The operation of my improved safety device for elevators will have been already understood from the foregoing description. The 35 weight of the car on the main lifting-cables holds the sheaves *F F'* with one or more turns of the counterbalance-cable wound on them, and prevents their turning in either direction while the car is moving up and down in its 40 well; but if the lifting-cables break or the strain on them is released from any cause, the counterbalance-weight, through its cables, will cause the sheaves to revolve, thereby, by means of the screws *G G'*, drawing the clamps 45 *v v* together against the guideways, and causing sufficient friction to prevent the descent of the car. The movement of the car is arrested in a gradual manner and without jerk or strain, such as is produced by the safety devices now generally employed on elevators. 50

I have demonstrated the efficiency of the invention herein described by practical use under the most unfavorable conditions.

A counterbalance weighing one thousand pounds may be made to force the clamps *v v* against the guideways with a pressure of twenty or thirty tons.

I claim—

1. The combination, with the elevator-car *A* and guideways *B B'*, of the clamps *v v*, 65 screw *G*, and the lifting-cables and counterbalance-cables, substantially as described.

2. The combination, with the elevator-car *A* and guideways *B B'*, of the cross-beams *C C'*, screws *G G'*, and clamps *v v*, substantially 70 as described.

3. The combination, with the elevator-car *A*, guideways *B B'*, screw-clamps *v v*, lifting-cable *D*, counterbalance-cable *E*, and suitable corner pulley or pulleys, *o*, substantially 75 as described.

4. The combination, with the car *A*, of the cross-beams *C C'*, clamps *v v*, screw *G*, and nut *r*, substantially as described.

5. The combination, with the car *A* and 80 guideways *B B'*, of the cross-beams *C C'*, screws *G G'*, sheaves *F F'*, corner pulleys, *o o'*, and the lifting-cables and counterbalance-cables, substantially as described.

6. The herein described safety attachment, 85 for elevators, consisting, essentially, of a friction clamp attached to the car and engaging the guideways, in combination with actuating sheaves, and the lifting and counterbalance cables, the latter applied to the actuating-sheaves and wound in opposite directions thereon, substantially as described.

7. In combination, with an elevator-car and its guides, a friction-clamp attached to the car, a screw for actuating said clamps, a sheave or 95 pulley for rotating said screw, and a lifting-cable and counterbalance-cable applied to said sheave or pulley and acting thereon in opposition to each other to hold the screw stationary, whereby the clamp is held suspended 100 by opposing strains upon the lifting and counterbalance cables, and is applied by the counterbalance when the strain is relaxed upon the lifting-cable, substantially as described.
